(57) **CLAIM**

The ornamental design for an inventor's award trophy, as shown and described.

DESCRIPTION

FIG. 1 is a front side view of the inventor's award trophy of the present invention, all other sides being a mirror image thereof;

FIG. 2 is a top view of the inventor's award trophy of FIG. 1; and,

FIG. 3 is a bottom view of the inventor's award trophy of FIG. 1, which is flat and devoid of surface ornamentation.

1 Claim, 3 Drawing Sheets

FIG. 1

FIG. 2

FIG. 3
